W. C. WRIGHT

METHOD OF SLICKING HIDES

Filed March 14, 1927

UNITED STATES PATENT OFFICE.

WALLACE C. WRIGHT, OF BROOKFIELD, NEW HAMPSHIRE, ASSIGNOR TO HARDING ENGINEERING COMPANY, OF EAST BOSTON, MASSACHUSETTS, A CORPORATION OF MASSACHUSETTS.

METHOD OF SLICKING HIDES.

Application filed March 14, 1927. Serial No. 175,199.

My present invention relates to the manufacture of leather and more particularly to an improved method ofslicking hides during the process of manufacture thereof.

5 In the manufacture of leather from hides or skins as practiced at the present day, attempts are being constantly made to produce leather with a smooth outer surface and in thus attempting to produce leather of this character, various schemes have been suggested for smoothing out the hide or skin while wet and maintain it in a smoothed out condition until the hide or skin has dried. It has been found that in doing this, that 10 unless the hide or skin is thoroughly smoothed out, that bubbles or soft places in the hide or skin will occur and it appears to be impossible to remove such soft spots in subsequent operations. The operation of 15 smoothing out the hide or skin while in a wet condition is known as "slicking", and while advantageous, is of no avail unless it can be produced cheaply enough.

As heretofore produced, the slicking operation is essentially a hand operation and, as great strength is required in smoothing or slicking out the hide or skins, it is a laborious operation and, therefore, necessarily a slow one.

20 In my present invention I have devised a method of slicking hides or skins which will materially expedite the performance of the operation to such an extent that it may be economically practiced and by substituting 25 a slicking or smoothing out machine, such as is described and claimed in my copending application, Serial No. 190,748, filed May 12, 1927, I am enabled to dispense with the usual manual labor employed at this point 30 and find that the slicking machine does a better job in less time and at considerable less cost than it has heretofore been possible to do.

The object of my invention, therefore, is 35 an improved slicking process.

While my process may be advantageously practiced manually, I find it more economical to utilize certain types of machines. As, however, my invention is more economically 40 practiced by the use of machinery, I have elected to illustrate the machinery in connection therewith, and in the accompanying drawing, the figure illustrates in perspective the various steps of my improved process.

Referring to the drawing, therefore, 10 designates generally a so-called putting out 55 machine having as an integral part thereof endless chain conveyors 11 spaced apart from each other and having at the exit end thereof an inclined delivery table 12. Below the delivery table is an endless belt conveyor 13 which inclines forwardly and upwardly with the upper reach thereof moving in the direction of the arrow shown. The endless chain conveyors 11 of the putting out 60 machine 10 will transport a hide or skin 14 through the putting out machine and deliver the same onto the inclined delivery board 12, from which the hide or skin 14 65 will drop onto the conveyor 13 and by means 70 of which it is transported upwardly and forwardly. At the delivery end of the endless conveyor 13 is placed a roll 15 which dips into a pan or vat 16 carrying paste or other adhesive in liquid or semi-liquid form, means 75 being supplied as electric heat through the conductor 17 for maintaining the adhesive in the pan 16 at the proper temperature. Beneath the roll 15 and also beneath the 80 pan 16 is located an endless conveyor 18, the upper surface of which moves in the direction of the arrow shown, and adjacent the delivery end of the conveyor 18 is a work-table or platform 19 of a slicking machine, preferably similar in character to the 85 slicking machine described and claimed in my co-pending application above referred to.

Adjacent to and at one side of the endless conveyor 18 is a table or platform 20, on which is or may be mounted a plurality of 90 cardboards 21 on which it is desired to slick or place the hides or skins 14. An operator stands between the platform 20 and the conveyor 18 and grasping one of the cardboards 21, places such cardboard under the 95 pan 16 and on the endless conveyor 18 in such a position that the hide or skin 14 will be properly positioned on the cardboard 21, as the endless conveyor 18 moves onward and as the roll 15 rotates, it being assumed 100 that the surface speed of the roll 15 is approximately equal to the surface speed of the endless conveyor 18. It is to be understood, of course, that the roll 15 in its rotation in the pan 16 will be covered with a layer of 105 adhesive, which layer of adhesive will be transferred to the hide or skin 14 as the same passes therethrough. It will be ob-

vious, therefore, that as the endless conveyor 18 moves and the roll 15 rotates, that the hide or skin 14 appearing in the drawing will be positioned on the cardboard 21 and will, in due course, be delivered to the base or platform 19 of theslicking machine. An operator stands at the slicking machine and properly positions the cardboard 21 with the hide or skin 14 thereon under a plurality of 10 radially movable slicking arms 22 each carrying a slicking blade or knife 23. The action of the slicking arms 22 and slicking blades 23 is practically automatic or may be made so by proper manipulation of the circuits controlling the operating motor 24 for 15 the arms 22, and after the slicking operation has been performed, the operator slides the cardboard 21 with the slicked hide 14 thereon onto an endless conveyor 25, which delivers it to any convenient point where it 20 may be hung up and dried, or, preferably further operations performed thereon prior to the drying operation.

It will be obvious from the above that by 25 taking the hide or skin 14 as it is delivered from the putting out machine 10 and associating therewith a cardboard 21, that the operation of placing the hide or skin 14 on the cardboard is eliminated and that by 30 smoothing it out preparatory to the slicking operation and then placing the hide or

skin in position to be operated on by the slicking blades 23, that the operation of slicking is greatly facilitated and the operation may be performed by the ordinary workman as distinguished from the extremely strong workman who was the only person who could heretofore perform this useful operation. 35

Having thus described my invention, what 40 I claim as new is:

1. That improved process of slicking hides which consists in moving a hide or skin onward as a single sheet, simultaneously placing thereunder while moving at the same 45 speed a slicking board, slicking the hide on the slicking board while thus positioned and then drying the hides.

2. That improved process of slicking hides or skins which consists in feeding a hide or skin forwardly, applying an adhesive to the hide or skin during its forward motion, positioning a slicking board with respect to the hide or skin and moving the same forwardly at the same speed to receive the hide 50 or skin, slicking the hide while thus positioned on the slicking board and moving the same forward to a dryer. 55

In testimony whereof, I have signed my name to this specification.

WALLACE C. WRIGHT.
